UNITED STATES PATENT OFFICE.

WILLIAM ARTHUR COLLINGS, OF KANSAS CITY, MISSOURI.

INSERT.

1,260,331.

Specification of Letters Patent. Patented Mar. 26, 1918.

Application filed December 27, 1915. Serial No. 68,810.

To all whom it may concern:

Be it known that I, WILLIAM A. COLLINGS, a citizen of the United States, and a resident of Kansas City, in the county of Jackson and State of Missouri, have invented certain new and useful Improvements in an Insert; and I do hereby declare that the following is a full, clear, and exact description of the same, reference being had to the accompanying drawings, and to the numerals of reference marked thereon, which form a part of this specification.

In concrete buildings it, of course, becomes necessary to provide suitable supports on the ceilings and the floors for the attachment of machinery and the like, but since it is very difficult and expensive to install such supports after the building has been finished and due to the unsatisfactory results obtained from such supports after installation, it has become the practice in structural concrete work to anticipate the requirements for such supports, and accordingly inserts of sufficient strength are embedded in the concrete ceilings and floors at the time of building to meet future requirements.

It is a well known fact, in concrete engineering, that approximately the lower half of a concrete floor or beam is normally in tension while the upper half is under compression, these stressed portions having what is termed a neutral plane or axis therebetween. Any loads imposed upon the concrete member should preferably be so disposed that the stresses resulting therefrom are located in the compression or upper part of the concrete above the neutral axis in order to obtain the greatest factor of safety.

Heretofore the manufacturers of inserts for use in concrete constructions, have disregarded the vital factors of adhesion or bonding, and also the proper construction and location of the inserts in relation to the neutral axis of the concrete member. Another difficulty encountered in the past in the manufacture of inserts, lies in the fact that the inserts are shaped to afford flanges or projections having sharp edges and corners which, under load, tend to split and

form line-cleavages in the concrete construction, thus producing a weakened and dangerous structure.

This invention relates to an insert having an opening in the base thereof adapted to removably engage or hold bolts or other fastenings for attaching, supporting or retaining pipes, machinery, shaft hangers, rails, or other mechanisms upon ceilings, floors or walls of concrete structures. The insert is constructed with projecting portions having rounded corners and edges, and integral corrugations around the exterior thereof, and is adapted to be embedded in concrete with the interior of the base accessible and with the upper portions of sufficient length to permit the same to extend into the concrete beyond and above the neutral axis and into the upper or compression part of the concrete so that the insert will have its major sustaining portion above the neutral axis, said rounded edges and corners insuring a good bond to be formed between the concrete and the insert, without danger of cracking or splitting the concrete.

It is an object of this invention to form an insert of sufficient depth or length to insure a large portion of the exterior surface thereof bonding in the concrete above the neutral axis of the concrete structure in which the insert is embedded.

It is also an object of this invention to construct an insert having a hollow base provided with exterior rounded corrugations, and with an integral upright portion having rounded projections thereon, said insert, when embedded in a concrete floor or beam, adapted to extend therethrough beyond the neutral axis thereof with the upright portion embedded in the upper or compression half of the floor or beam, permitting an excellent bond to be formed between the concrete and the insert around said rounded corrugations and projections.

It is also an important object of this invention to construct an insert adapted to be embedded in a concrete structure without interference with the reinforcing members and with one portion thereof projecting

into and bonding in the compression part of the floor or beam to form a monolithic construction free from the danger of cracking.

It is also an object of this invention to construct an insert having a corrugated base and anchor, adapted to be embedded in a concrete structure to obtain the greatest supporting effect therefrom, said base cored out to receive removably therein an attaching member for supporting mechanisms from the ceiling or upon the floor of a concrete building, or fastening a rail to a concrete tie.

It is a further object of this invention to construct a corrugated insert having a hollow tapered base adapted to removably receive an attaching bolt removable therein, and with the upper portion of said insert surrounded by a coiled reinforcement member to increase the strength of the concrete around the insert.

It is furthermore an object of this invention to construct an insert having a tapered hollow base with exterior rounded corrugations, adapted to receive detachably engaged therewith a supporting bolt, and provided with an integral upright anchor extension member having a plurality of corrugations integral therewith spaced from one another and decreasing in size from the upper end down to the base to obtain the greatest sustaining effect from the concrete in which it is embedded.

It is finally an object of this invention to construct an insert of simple and durable construction adapted to be embedded in concrete with the corrugated anchor portion thereof disposed above the neutral axis of the concrete structure to derive the greatest retaining effect therefrom.

The invention (in a preferred form) is illustrated in the drawings and hereinafter more fully described.

In the drawings:

Figure 1 is a section through a concrete floor having embedded therein a ceiling support embodying the principles of my invention.

Fig. 2 is a view similar to Fig. 1, showing the base of the embedded device in section.

Fig. 3 is a cross section of a concrete floor having embedded therein the device in an inverted position to afford a floor attaching means.

Fig. 4 is a view similar to Fig. 1, illustrating a modified form of the device.

Fig. 5 shows a modified form of the device in elevation having two anchor members, with the device embedded in the underside of a concrete floor as a ceiling support.

Fig. 6 is a top plan view of the device shown in Fig. 5.

Fig. 7 is a bottom plan view thereof.

Fig. 8 is a section taken on line 8-8 of Fig. 6.

Fig. 9 is a section taken on line 9-9 of Fig. 8.

Fig. 10 is a bottom plan view of a modified form of the device.

Fig. 11 is a top plan view of another modified form of the device, with the base omitted.

Fig. 12 is a fragmentary detail section of a portion of the slotted base showing a liner for use with small sized bolts.

As shown on the drawings:

The reference numeral 1, designates a concrete floor having reinforcing rods 2, and an insert embedded therein, said insert comprising a base 3, with the sides and ends thereof tapered downwardly and inwardly, and having integrally formed around the outer periphery thereof a plurality of rounded corrugations 4. A threaded aperture 5, is provided in said base 3, extending upwardly from the bottom thereof adapted to receive a threaded stud or bolt 6, or any other suitable supporting means, threaded therein for securing machinery or the like to ceilings or floors of concrete buildings. Integrally formed on said base 3, and projecting upwardly from the upper surface thereof is a suspending arm or anchor 7, having an integral flat circular top 8, and integral flat circular flanges or projections 9, extending outwardly at right angles to said arm and spaced one below the other with a gradual decrease in the diameter of said flanges from the upper to the lowermost one thereof. Formed or drilled in the surfaces of each of the sides and ends of the base 3, at the middle of the lower edges thereof, are recesses 10, each adapted to receive a nail for securing the insert to the wooden form or mold to hold the insert in place particularly during the pouring of the concrete.

In the modified form of device shown in Fig. 4, the construction of the insert is exactly the same as that above described with the exception that a spiral coil 11, is slipped over the anchor member 7, and spaced therefrom to permit the concrete to pass therethrough to bond around said insert and spiral, thus greatly reinforcing the concrete immediately surrounding the insert for sustaining heavy loads.

Figs. 5 to 9, inclusive cover a modified form of insert having two or more suspending or anchor members, constructed as already described, integral with the upper surface of an elongated base 12, the sides and ends of which are tapered downwardly and inwardly, and integrally formed around the outer periphery of said base 12, are a plurality of rounded corrugations 13, spaced at intervals below one another. Formed or

machined in the lower central portion of each of the ends and sides of the base 12, are tapering recesses 14, each adapted to receive a nail for securing the insert in place 5 in a wooden form or mold for the concrete. Cored within said base 12, is a long narrow recess 15, the lower wall 16, of which is identical with the lower wall of said base 12, having a longitudinal slot 17, therein, opening 10 at one end into a substantially square enlargement 18, adapted to receive the head of a bolt 19, therethrough, to permit the bolt to be slidably engaged in the slot 17, with the threaded portion thereof projecting outwardly to receive a nut or other object 15 thereon. To prevent the bolt head from accidentally sliding or working its way out of the recess 15, lugs or projections 20, are integrally formed on the inner surface of 20 the wall 16, on each side of the open end of the slot 17.

In the modified form of the device shown in Fig. 10, the construction of the anchor members is the same as that shown in Fig. 5, 25 said arms integrally formed upon an L-shaped base having a long leg 21, and a short leg 22, at one end thereof and at right angles thereto. Integral with the sides and ends of the base are peripheral rounded corrugations 23, and spaced at intervals at the center on the exterior of and near the bottom of said base sides and ends are recesses 30 24, affording a means for securing the device in position in a mold. Cored out of the leg 35 21, of the base is a long narrow slot 25, having a short slot 26, at one end thereof and at right angles thereto communicating with a square enlargement 27, formed in the short leg 22, of the base, and adapted to receive 40 the head of a bolt inserted therethrough to permit the bolt to be engaged in the slot 25.

Fig. 11, is a top plan view of a modified form of an anchoring arm having a star-shaped top 28, to allow the concrete to flow 45 easily therearound and prevent the formation of pockets beneath said top.

The fragmentary section of the base 12, shown in Fig. 12, has a small sized bolt 29, slidably mounted in the slot 17, and to prevent 50 said bolt from turning in the recess 15, a liner 30, is removably placed around the head of the bolt, thus making it possible to use bolts of various sizes with the inserts.

The operation is as follows:

When it is desirable or necessary to support or suspend machinery, or the like, from the ceilings of a concrete building, the inserts are first positioned with the base thereof resting on the floor of a wooden form or 55 mold and held in place by means of nails engaging the recesses 10, of the insert. The reinforcing rods 2, are then installed on both sides of the inserts after which the mold is filled with concrete, which due to the round-

ed surfaces, corners and edges of the tops 8, 60 flanges 9, and the corrugations 13, thoroughly molds around the insert and forms a bond therewith. After the concrete has set and hardened the mold is removed and the machinery or machinery supports may 65 be secured in place by means of the bolts 6, which engage the machinery, and are threaded into the threaded apertures 5, of the inserts. With the anchor members 7, extending 70 into the upper or compression part of the concrete floor 1, above the neutral axis and with the base 3, tapered as described, the insert is prevented from withdrawal from the concrete and the structure 75 is capable of sustaining great loads without 80 danger of the concrete splitting or cracking thus weakening the structure. In fastening machinery on concrete floors, the inserts are simply inverted with the bottom of the base 85 3, flush with the surface of the concrete floor, as shown in Fig. 3. For the purpose of supporting extra heavy loads, a spiral 11, is slipped over the anchor member 7, for reinforcing the concrete immediately surrounding the insert. 90

The gang inserts shown in Figs. 5 to 10, inclusive, are bonded into the concrete, as above described, the connecting or retaining bolts 19, having their heads inserted through the square enlargements 18 or 27, and moved 95 so that the threaded shanks of the bolts may project outwardly through the slots 17, or 25, respectively, to permit the attachment of mechanisms thereto. Bolts of different sizes may be used with the slotted inserts 100 and to prevent the small sized bolts from turning in the recess 15, liners 30, are placed around the heads of the bolts.

It will, of course, be understood that the inserts may be made with a plurality of 105 anchor members, with the tops and flanges thereof of various shapes, and having recesses in the base thereof adapted for receiving a number of supporting bolts. The details of construction may be varied through 110 a wide range without departing from the principles of this invention, and I therefore do not purpose limiting the patent granted otherwise than necessitated by the prior art.

I claim as my invention:

1. An insert for concrete, comprising a tapered base having formed integrally thereon a plurality of rounded corrugations, and an anchor formed integrally with said base, said anchor having an integral flat outer 120 end and having bonding elements disposed between its end and the tapered base.

2. An insert for concrete, comprising a tapered L-shaped base, one wall of said base having registering long and short slots conforming to the L-shape of said base, the short slot being formed with an enlargement, a bolt adapted to have the head thereof 125

inserted through said enlargement to permit said bolt to be shifted to engage the longer slot, and anchoring means integrally formed on said base.

5. An insert for concrete, comprising a corrugated tapered base having recesses in the sides thereof to permit attachment to a mold, tapered suspending means integral with said base, and a coiled member engaged

thereover and spaced therefrom to reinforce 19 the concrete molded around said insert.

In testimony whereof I have hereunto subscribed my name in the presence of two subscribing witnesses.

WILLIAM ARTHUR COLLINGS.
